(57) **CLAIM**

The ornamental design for a vaporization rig, as shown and described.

DESCRIPTION

FIG. 1 is a top perspective view of a vaporization rig; FIG. 2 is a bottom perspective view of the vaporization rig of FIG. 1;

FIG. 3 is a front view of the vaporization rig of FIG. 1; FIG. 4 is a back view of the vaporization rig of FIG. 1; FIG. 5 is a first side view of the vaporization rig of FIG. 1; FIG. 6 is a second side view of the vaporization rig of FIG. 1;

FIG. 7 is a top view of the vaporization rig of FIG. 1; FIG. 8 is a bottom view of the vaporization rig of FIG. 1; and,

FIG. 9 is a top perspective view of the vaporization rig of FIG. 1 shown in an environment of use.

The broken lines in the drawings illustrate environmental subject matter only and form no part of the claimed design.
